AMINOALKYL ESTERS OF DITHIENYL
ALIPHATIC ACIDSFrederick F. Blicke, Washtenaw County, Mich.,
assignor to Regents of the University of Michigan,
Michigan, Ann Arbor, Mich., a corporation of MichiganNo Drawing. Application August 17, 1946,
Serial No. 691,409

8 Claims. (Cl. 260—294.3)

1

This invention relates to certain basic-alkyl esters of thieryl-substituted (alpha-thienyl) aliphatic acids, the salts of such esters, and pharmaceutical products in which they are employed as active ingredients. This application is a continuation-in-part of my prior-filed copending application Serial 575,929, filed February 2, 1945, which has been abandoned.

The basic-alkyl esters of the present invention have the following generic formula

wherein m represents zero or a positive integer from 1 to 5, inclusive, n represents zero or a positive integer from 1 to 5, inclusive, the carbon chain is straight or branched and contains from 1 to 8 carbon atoms, inclusive, X is hydrogen or hydroxy, and Z is alkylamino, dialkylamino, or a piperidino ring. The term "alkyl," as employed in "alkylamino" and "dialkylamino," indicates a radical of straight or branched chain structure and preferably containing from 1 to 8 carbon atoms, inclusive. Representative alkyl groups are methyl, ethyl, propyl, isopropyl, butyl, isobutyl, tertiary butyl, amyl, n-octyl and the like.

A principal object of the invention is the provision of a series of compounds having utility as pharmaceuticals and particularly as antispasmodic agents. Members of this new group of compounds have been prepared, identified and found to have value in antispasmodic preparations for the relief of muscle spasm as determined by the method of Magnus (described in Dennis E. Jackson, "Experimental Pharmacology and Materia Medica," second ed., 1939, St. Louis, C. V. Mosby Co., page 516). The compounds also appear to have local anesthetic and mydriatic effects.

The free basic esters of this group of compounds are usually oily liquids with relatively high boiling points, while the acid or quaternary ammonium salts thereof are usually crystalline solids at ordinary temperatures. The compounds included within the scope of the present invention are (a) amines of the general formula

wherein m , n , the carbon chain, X and Z have the values disclosed in the formula given above; and (b) salts thereof. Instead of the simple thieryl radical, the thiophene nucleus may contain substituents.

2

Within the meaning of the term "salts" are included both acid salts such as the citrate, tartrate, hydrochloride, hydrobromide, hydrosulfate, and many others, as well as the quaternary ammonium salts such as the methobromide, ethochloride and ethyl para-toluenesulfonate. The acid salts may be prepared from the free basic ester by treatment with the selected acid, while the quaternary ammonium salts are prepared by treatment of the free basic ester with the desired alkyl halide or aryl sulfonic ester. When the ester is formed by a reaction of an acid and an alkyl halide, or by the reaction of an acid halide and an alcohol, the ester usually precipitates as the hydrohalide salt.

The thieryl-substituted fatty acids employed as starting materials may be prepared by first reacting thiophene with an acid halide of an alkyl monoester of oxalic acid, e. g., ethyl oxalyl chloride, $\text{ClCO}-\text{COOC}_2\text{H}_5$, in the presence of aluminum chloride to produce an alkyl ester of alpha-thienyl glyoxylic acid, such as ethyl (alpha-thienyl) glyoxylate

25 The keto acid is then reacted with a thiophene-substituted Grignard reagent and the resulting complex decomposed with a suitable acidic reagent, such as HCl , NH_4Cl , NaHSO_4 , et cetera, to produce a substituted hydroxy aliphatic acid having two thieryl radicals attached to carbon atoms of the aliphatic chain. This compound may be employed without further modification in the production of the basic ester, or it may be reduced, e. g., with stannous chloride, to produce the corresponding hydroxyl-free thieryl-substituted fatty acid and thereafter treated to prepare the basic ester.

30 The compounds of this invention are also obtained by a procedure which may be as follows, using beta-diethylaminoethyl (alpha-thienyl)-methyl-beta-(alpha-thienyl) ethylacetate hydrochloride as an example: beta'-(alpha-thienyl)-ethyl chloride, prepared from (alpha-thienyl)-magnesium bromide and beta-chloroethyl para-toluenesulfonate, was converted to diethyl beta'-(alpha-thienyl) ethylmalonate by reaction with diethyl malonate and sodium ethylate in an alcoholic medium. The monosubstituted diethyl malonate was then converted by the usual procedure into the disubstituted diethyl malonate. (Some mono- and disubstituted malonic esters are given in Table I.) The disubstituted malonic ester is then converted to the acid by treatment with alkali solution, the malonic acid is converted to the acetic acid by heating, and the acetic acid is then reacted with the selected substituted aminoalkyl halide, in this instance beta-diethylaminoethyl chloride, according to the general

method of Horenstein and Pählicke, *Berichte* 71, 1644 (1938), to prepare the desired ester, beta-diethylaminoethyl (alpha-thienyl) methyl-beta'-(alpha-thienyl) ethylacetate hydrochloride. (Some substituted thienylmalonic and thienyl-acetic acids are listed in Table II.)

In a similar manner many other members of this new group of compounds may be prepared. As representative of these new compounds may be mentioned 2-monobutylaminoethyl (alpha-thienyl) methyl - (alpha-thienyl) acetate hydrochloride, 3-monomethylaminopropyl beta-(alpha-thienyl) ethyl - (alpha-thienyl) - methylacetate hydrobromide, 4-monoethylaminobutyl gamma-(alpha-thienyl) propyl - (alpha-thienyl) acetate methobromide, 3-dibutyl-aminopropyl beta-(alpha-thienyl) ethyl - gamma'-(alpha-thienyl) - propyl-acetate ethochloride, 3-monoethylaminobutyl(alpha-thienyl)-methyl-(alpha-thienyl)-acetate ethyl (para-toluene)sulfonate, 2,2-di-methyl - 3 - dimethylaminopropyl beta-(alpha-thienyl) ethyl-beta'-(alpha-thienyl) ethylacetate hydrosulphate, 2 - dipropylamino - ethyl(alpha-thienyl) methyl(alpha-thienyl) acetate hydrochloride, et cetera. Other esters will be evident from an inspection of Table III.

Hydroxyl-containing esters which are prepared according to the method herein disclosed include 2-monoethylaminoethyl di-(alpha-thienyl) hydroxyacetate hydrochloride, 2-piperidinoethyl(alpha-thienyl) methyl - (alpha-thienyl) methylhydroxyacetate hydrobromide, 3-dipropylaminopropyl beta-(alpha-thienyl) ethyl-beta'-(alpha-thienyl) ethyl-hydroxyacetate hydrochloride, 2 - dibutyl - amino - ethyl(alpha-thienyl) methyl-(alpha-thienyl) methylhydroxyacetate methobromide, 2 - diethyl - aminopropyl beta-(alpha-thienyl) - ethyl-gamma'-(alpha-thienyl) propylhydroxyacetate hydrochloride, and the like.

In the preparation of the hydrohalides of the basic-alkyl esters of the thienyl-substituted aliphatic acids, substantially equimolar proportions of a basic-alkyl halide and the thienyl-substituted acid are admixed in a suitable solvent, e. g., isopropyl alcohol, and the mixture heated until reaction has occurred. This may require heating at reflux for from 2 to 16 hours. The crude salt may be crystallised by dissolving in a small quantity of warm ethanol, adding diethyl ether until turbidity and thereafter cooling the mixture. The hydrohalide salt separates in crystalline form and is recovered by decantation or filtration. Other acid salts may be obtained in a similar manner from the free basic ester. As the antispasmodic activity of the esters apparently resides in the ester itself and not in the salt portion of the molecule, any acid salt may be employed without detracting materially from the effectiveness of the compound, provided only that the anion of the acid be reasonably non-toxic. The salt to be produced is usually chosen primarily with regard to crystallinity and solubility.

As an alternative method of salt formation, a non-hydroxy acid may be converted to the acid chloride, as by heating with thionyl chloride, and the acid chloride then reacted with the selected basic alcohol to form the desired ester hydrochloride. The former method is preferred, however, since higher yields of product are obtained thereby.

The free basic-alkyl esters may be obtained from the hydrohalides by treatment with aqueous sodium carbonate or other mild alkali, pref-

erably at low temperatures, and thereafter extracting with ether or other suitable solvent. The solution may then be dried and the solvent volatilised in accordance with conventional methods.

To produce quaternary ammonium salts, the free base may be treated with alkyl halides, such as methyl bromide, ethyl chloride, propyl iodide, et cetera, or with the selected aryl sulfonic ester such as ethyl para-toluenesulfonate, under which conditions the corresponding quaternary salt, e. g., the methobromide, ethochloride, or ethyl para-toluenesulfonate, is usually formed in high yields.

15 The following examples will serve to illustrate procedures whereby the production of members of this new group of compounds may be accomplished, but are in no way to be construed as limiting.

20 *Preparation 1.—(Alpha-thienyl) methyl chloride*

A rapid stream of hydrogen chloride was passed into a stirred mixture of 525 milliliters of concentrated hydrochloric acid, 450 milliliters of 40 per cent aqueous formaldehyde and 465 milliliters of thiophene at a temperature between zero and five degrees centigrade. After saturation with the gas, the material was poured into two liters of water, the oily precipitate separated, and the aqueous layer extracted several times with ether. Extracts and the oil were combined, washed with water and dried over potassium carbonate. After removal of the ether, the product boiled at 78-82 degrees centigrade at 18 millimeters of mercury pressure. The yield was 373 grams or 47 per cent of the theoretical.

The chloride should not be kept in a tightly closed container since it undergoes spontaneous decomposition, often with explosive violence. If preserved in a refrigerator, the compound remains undecomposed for some time.

45 *Preparation 2.—(Alpha-thienyl) acetonitrile*

A mixture of 133 grams of (alpha-thienyl)-methyl chloride, 60 milliliters of acetone and 74 grams of sodium cyanide dissolved in 100 milliliters of water was stirred and heated in a water-bath at 60-65 degrees centigrade for four hours. Water was added, the organic layer separated and added to the ether extract of the aqueous layer. The ether was removed from the dried solution and the nitrile distilled. The nitrile boiled at 115-120 degrees centigrade at 22 millimeters of mercury pressure. The yield was 100 grams of 81 per cent of the theoretical.

60 *Preparation 3.—Ethyl(alpha-thienyl) acetate*

A mixture of 100 grams of (alpha-thienyl)-acetonitrile, 225 milliliters of 95 per cent alcohol and 7 milliliters of water was saturated with hydrogen chloride at a temperature between zero and five degrees centigrade. After 12 hours at room temperature, the mixture was heated for two hours on a steam-bath, cooled, 150 milliliters of water added, the oily layer separated and added to the ether extract of the aqueous layer. The solution was dried and the solvent removed. The desired product was obtained in 66 per cent yield (93 grams) and boiled at 119-121 degrees centigrade at 23 millimeters of mercury pressure.

Preparation 4.—Beta'-(alpha-thienyl)ethyl chloride

A solution of (alpha-thienyl)magnesium bromide (prepared from 97.8 grams of alpha-bromo-thiophene, 14.6 grams of magnesium and 375 milliliters of ether) was stirred and 280 grams of beta-chloroethyl para-toluenesulfonate, dissolved in 300 milliliters of ether, was added dropwise. A solid began to precipitate after about one-half of the ester had been added. The mixture was stirred and refluxed for five hours, cooled to between five and ten degrees centigrade, and 100 milliliters of concentrated hydrochloric acid diluted with 350 milliliters of water was added thereto. An amount of water sufficient to dissolve the precipitate was then added; the ether layer was washed with sodium bicarbonate solution and dried with potassium carbonate. The chloride boiled at 88-92 degrees centigrade at 20 millimeters of mercury pressure. The yield was 62.6 grams or 71.4 per cent of the theoretical. The analysis showed the product to contain 24.06 per cent chlorine as compared with the theoretical of 24.19 for C_6H_5SCl .

Preparation 5.—Diethyl(alpha-thienyl)malonate

A solution prepared from 18.5 grams of sodium and 300 milliliters of alcohol was heated in an oil-bath, stirred, and the alcohol removed under reduced pressure. The cake of sodium ethylate was broken into small pieces and 650 milliliters of diethyl carbonate was added, followed by 132.4 grams of ethyl(alpha-thienyl)-acetate. The mixture was stirred at 80-85 degrees centigrade and the alcohol was removed, as fast as formed, at 300-320 millimeters of mercury pressure. After five hours, the distillate, a mixture of alcohol and diethyl carbonate, amounted to about 200 milliliters. The material was poured into a mixture of water and ice to which 90 milliliters of concentrated hydrochloric acid had been added. The organic layer was separated, combined with the benzene extract of the aqueous layer and shaken with water. After removal of excess benzene and diethyl carbonate, the product (117 grams) boiled at 148-151 degrees centigrade at 6 millimeters of mercury pressure.

Preparation 6.—Diethyl beta'-(alpha-thienyl)-ethylmalonate

A solution of sodium ethylate (prepared from 7.8 grams of sodium and 135 milliliters of ethanol) was warmed to 50 degrees centigrade and 81.5 grams of diethyl malonate was added thereto. The mixture was heated to the boiling point and 50.5 grams of beta'-(alpha-thienyl)ethyl chloride was added slowly. The mixture was refluxed for twenty hours, alcohol removed under reduced pressure, water added to the oily residue and the mixture neutralized with dilute hydrochloric acid. The organic layer was separated and combined with the benzene extract of the aqueous layer. After removal of solvent, the ester boiled at 150-154 degrees centigrade at 4 millimeters of mercury pressure. The yield was 46.7 grams or 51 per cent of the theoretical.

Preparation 7.—Diethyl(alpha-thienyl)methyl-beta'-(alpha-thienyl)-ethylmalonate

A solution, obtained from 4.3 grams of sodium and 140 milliliters of alcohol, was warmed to 50 degrees centigrade and 37.8 grams of diethyl beta'-(alpha-thienyl)ethylmalonate was added.

After the mixture had refluxed for a few minutes, 24.9 grams of (alpha-thienyl)methyl chloride was added dropwise at a rate such that the mixture continued to reflux. After about three hours at reflux, the product was isolated in the usual manner.

Preparation 8.—(Alpha-thienyl)methyl-beta'-(alpha-thienyl)ethylmalonic acid

- 10 A mixture of 36.3 grams of diethyl(alpha-thienyl)methyl-beta'-(alpha-thienyl)ethylmalonate and 19.6 grams of potassium hydroxide, dissolved in 20 milliliters of water and 78 milliliters of alcohol, was refluxed for twenty hours.
- 15 The water and alcohol were then removed under reduced pressure, the residue dissolved in a small amount of water, the solution cooled to about five degrees centigrade, 50 milliliters of ether added and the mixture acidified with concentrated hydrochloric acid. The ether layer was separated and mixed with the ether extract of the aqueous layer. After washing the ether solution with water, it was dried over magnesium sulfate and the solvent removed to yield 25.5 grams of the desired product. The yield was 82 per cent of the theoretical.

Preparation 9.—(Alpha-thienyl)methyl-beta'-(alpha-thienyl)-ethylacetic acid

- 30 Ten grams of the corresponding malonic acid was heated to 175-185 degrees centigrade for a period of about one hour and the material thereafter distilled. The yield of the desired substituted acetic acid was usually of the order of 35 77 per cent of the theoretical.

EXAMPLE 1.—2-diethylamino-ethyl (alpha-thienyl)-methyl-beta'-(alpha-thienyl)ethylacetate hydrochloride

- (Alpha-thienyl)methyl-beta'-(alpha-thienyl)ethylacetic acid (6.8 grams) as obtained in Preparation 9 hereinbefore, 3.5 grams of 2-diethylaminoethyl chloride and 80 milliliters of anhydrous isopropyl alcohol were refluxed for 48 hours and the mixture then allowed to cool in a refrigerator. The ester hydrochloride precipitated from the solution and was filtered therefrom. The yield was 5.2 grams of 51 per cent of the theoretical.

Preparation 10.—Di-(alpha-thienyl)hydroxyacetic acid

- 50 This acid was prepared by reacting 98 grams (0.6 mole) of alpha-thienyl bromide with 14.4 grams of magnesium in 300 milliliters of diethyl ether to form a solution of alpha-thienyl magnesium bromide and adding this solution portionwise, with stirring, to an ethereal solution of 31.2 grams (0.2 mole) of (alpha-thienyl)glyoxylic acid. The insoluble residue from this reaction was washed successively with anhydrous diethyl ether and saturated ammonium chloride solution, and then filtered. The residue from the filtration was washed with acetone and dispersed in dilute aqueous hydrochloric acid. The dispersion was filtered, the residue extracted with five per cent aqueous sodium bicarbonate, the alkaline solution clarified with activated carbon, acidified and filtered. The 20 grams of di-(alpha-thienyl)hydroxyacetic acid so obtained melted at 93 degrees centigrade.

70 OTHER EXAMPLES

By a condensation of the above or related hydroxy-acids with the selected substituted aminoalkyl halide, the desired hydroxyl-containing ester is produced in high yields. The condensation of di-(alpha-thienyl)hydroxyacetic acid and

2-diethylaminoethyl chloride, for example, is productive of 2-diethylaminoethyl di-(alpha-thienyl)hydroxy acetate hydrochloride, while the condensation of 4-dipropylaminobutyl chloride and (alpha-thienyl)ethyl-beta'-(alpha-thienyl)ethylhydroxyacetic acid produces 4-di-propylaminobutyl(alpha-thienyl)-beta'-(alpha-thienyl)ethylhydroxyacetate hydrochloride.

In Table I hereinafter are listed properties of several diethyl esters of alpha-thienyl-substituted malonic acids prepared in accordance with the general methods described hereinbefore.

Table I.—*Mono- and disubstituted malonic esters*

	RCH(COOC ₂ H ₅) ₂		RR'C(COOC ₂ H ₅) ₂	
	R	B. P., °C.	R	B. P., °C.

Di-(alpha-thienyl) acetic acid, C₁₀H₈O₂S₂, as disclosed in patent application Serial No. 575,929, melts at 91-94 degrees centigrade.

Malonic acid 1 lost carbon dioxide spontaneously to form the corresponding acetic acid.

Malonic acid 2 was recrystallised from water; 3 from a mixture of benzene and acetone; the acetic acids were recrystallised from petroleum ether.

Other examples.—In Table III hereinafter are listed properties of other specific compounds that are preferred embodiments of the invention.

Table III.—*Hydrochlorides of esters of some substituted (alpha-thienyl) aliphatic acids*

¹ alpha or 2-thienyl.

² hydrobromide.

³ piperidino.

⁴ methobromide.

All of the compounds were recrystallised from a mixture of absolute alcohol and ether.

Various modifications may be made without departing from the spirit or scope of the present invention, and it is to be understood that I limit myself only by the appended claims.

I claim:

1. A compound selected from the group consisting of (a) basic-alkyl esters having the formula

wherein *m* represents an integer from 0 to 5, inclusive, *n* represents an integer from 0 to 5, inclusive, the carbon chain is an alkene radical

of the group consisting of straight and branched chain alkene radicals and contains from 1 to 8 carbon atoms, inclusive *X* is selected from the group consisting of hydrogen and hydroxy radicals, and *Z* is selected from the group consisting of alkylamino, dialkylamino and piperidino radicals, and (b) salts thereof.

2. A salt of a basic-alkyl ester having the formula

wherein *m* represents an integer from 0 to 5, inclusive, *n* represents an integer from 0 to 5, inclusive, the carbon chain is an alkene radical of the group consisting of straight and branched chain alkene radicals and contains from 1 to 8 carbon atoms, inclusive, *X* is selected from the

group consisting of hydrogen and hydroxy radicals, and Z is selected from the group consisting of alkylamino, dialkylamino and piperidino radicals.

3. A basic-alkyl ester having the formula

wherein m represents an integer from 0 to 5, inclusive, n represents an integer from 0 to 5, inclusive, the carbon chain is an alkene radical of the group consisting of straight and branched chain alkene radicals and contains from 1 to 8 carbon atoms, inclusive, X is selected from the group consisting of hydrogen and hydroxy radicals; and Z is selected from the group consisting of alkylamino, dialkylamino and piperidino radicals.

4. 2-diethylaminoethyl(2-thienyl)methyl-(2-thienyl)acetate hydrochloride.

5. 2-piperidinoethyl di-(2-thienyl)acetate hydrochloride.

6. 2-diethylaminoethyl di-(2-thienyl)acetate hydrochloride.

7. 2-diethylaminoethyl di-(2-thienyl)acetate hydrobromide.

8. 3-diethylaminopropyl di-(2-thienyl)acetate 30 hydrochloride.

FREDERICK F. BLICKE.
